PROCESS FOR SEPARATING WAX FROM
WAX-CONTAINING OILSWalter W. N. Meyer, Berlin, Germany, assignor
to Standard Oil Development Company, a cor-
poration of DelawareNo Drawing. Application May 18, 1938,
Serial No. 208,601

9 Claims. (Cl. 196—19)

The present invention relates to an improved method for separating waxy constituents from wax-bearing oils in order to produce dewaxed oils of low cold test. The invention particularly relates to the production of mineral oils of low cold test from petroleum oils which contain appreciable amounts of waxy hydrocarbons and is concerned more specifically with an improved method for removing amorphous waxy hydrocarbons from petroleum oils containing the same. The improved process of the present invention is obtained by utilizing in a dewaxing operation relatively inexpensive substances of the class of wool fat, wool grease or degras, cholesterol, lanolin and the like as wax modifying agents or dewaxing, filtering or wax separation aids.

It is well known in the art to separate the waxy constituents from wax-bearing mineral oils by various methods, all of which have in common the feature of solidifying the solid wax by cooling or chilling the oil to relatively low temperatures. The separation of the solid precipitated wax from the oil is then effected, for example, by allowing the precipitated wax to settle by gravity or by centrifuging or by filtering the oil either in the usual plate or frame presses or by means of centrifugal filters. It is also well known in the art to facilitate and accelerate the separation of the wax from the wax-bearing mineral oil by adding materials such as diluents and the so-called settling and filtering aids.

In the usual processes the oil is preferably diluted with various solvents as, for example, naphtha, octane, heptane, hexane, pentane, liquid butane and propane or other liquefied normally gaseous hydrocarbons either alone or in various combinations with each other. However, in dewaxing processes in which only a diluent was used, it was necessary to gradually cool the mixture over a period as high as several days since too rapid cooling of the liquid mixture caused the entire body to congeal into a semi-solid or pasty mass which could not be subsequently separated. This difficulty was overcome to some extent by the use of a small quantity of oil soluble substance known as separation aids which apparently modified the wax crystalline structure so that considerably greater cooling and filtering rates could be employed. These separation aids or wax modifiers were of various types and struc-

tures and were produced by a great many different methods. For example, asphaltic materials produced by high temperature oxidation of petroleum products have been used as well as asphaltic materials which are secured from heavy petroleum residues by precipitation with a known class of solvents which are miscible with the oil and precipitate the asphalts. Asphaltic materials obtained as residues in the distillation of asphaltic base oils are also satisfactory, as well as substances of the class of materials derived from paraffin wax.

The substances with which the present invention is concerned are of an entirely different type and structure and have not heretofore been used in dewaxing or dewaxing operations or similar processes. The substances of the present invention are of the class of wool fat, wool grease or degras, cholesterol and lanolin. Constituents of wool fat or wool grease as, for example, wool fat alcohols, wool fat stearine and wool fat ethers may be used also, as well as particular fractions of these substances which may be separated by known means as, for example, by distillation processes or by solvent treating processes.

These materials may be secured in any manner whatsoever and may be refined to any extent desirable. It may be preferable to use a particular constituent of the wool fat as, for example, cholesterol or to use a higher boiling fraction of the wool fat which is segregated by distillation or by means of selective solvents.

The separation aids of the present invention may be utilized in any concentration desirable. It is, however, preferred to add these materials in a concentration from 0.1 to 5.0%, preferably in the concentration from 0.5 to 2.0%.

It has been found that these materials greatly accelerate the separation of the waxy constituents from wax bearing petroleum oils. When substances of the present invention are employed, the rate of cooling can be greatly increased without solidification or gellation and the rate of settling of the waxy constituents is also greatly accelerated giving a clear separation. The substances of the present invention also aid in separation of the waxy constituents by centrifuging or by filtering.

These substances may be employed in dewaxing operations in which any particular type of dilu-

ent or solvent is employed. However, particularly desirable solvents are naphtha or solvents of the type which are heavier than the solid waxes themselves. Among the solvents included in this class 5 are halogenated aliphatic or aromatic hydrocarbons such as carbon tetrachloride, dichlorethane, difluoropropane, tribromethane, dichlorethylene, trichlorpropylene, chlorbenzol or toluol and the like. While these solvents may be used alone it is 10 preferred to use them in combinations, either with each other or some other materials such as benzol, toluol, xylool and petroleum naphthas, ranging from propane to octane and heavier. The solvent is preferably selected so as to have a freezing point considerably below the temperature at 15 which the wax separation is effective, also to have as low a solvent power for waxes at the separation temperature as possible, which makes for the least possible spread between wax separation temperature and the pour point of the oil produced. Particularly useful combinations of these types of 20 solvents are as follows:

	Per cent
Dichlorethane	75
25 Carbon tetrachloride	25
Dichloropropane	70
Carbon tetrachloride	30
30 Dichlorethane	50
Dichlorethylene	50
Dichlorethane	60
35 Trifluorethylene	40
Dichlorethane	70
Carbon tetrachloride	20
Trichlorethylene	10
40 Dichlor ethane	70
Benzol	30
Dichloropropane	75
45 Toluol	15
Xylool	10
Ethylene difluoride	70
Carbon tetrachloride	15
50 Naphtha	15

It should also be preferred to select such a combination of solvents, as those above, which do not tend to separate the oil into mutually insoluble 55 layers at or near the temperature of wax separation, and in which the separation aid is barely soluble. The composition of the solvent can be readily varied so as to bring about this condition and to produce a slight turbidity. When 60 the solvent dissolves the aid completely forming a clear solution, the separation aid is almost always of low activity.

These solvents or diluents may be present in any desired concentration depending upon the 65 particular solvent being used, the grade of oil being treated, the waxy constituents present, the grade of dewaxed oil desired, as well as upon the temperature of treatment. In general, these solvents or diluents are preferably present in the 70 concentration of from 1 to 4 volumes of solvent per one volume of oil being treated.

Other conditions of the dewaxing process such as pressure, temperature, rate of cooling, settling time, filtering rates and mode of separation of the 75 waxy constituents may be optimally adjusted

and depend to a large extent upon the oil being dewaxed, the concentration of the waxy constituents present, the grade of dewaxed oil desired and upon the particular solvent being used. Dewaxed oil suitable for certain purposes may be secured by chilling to a temperature of from 5 to 10° F., although a particularly desirable oil is secured by chilling to a temperature of from -20 to -30° F. or lower. The rate of chilling may be 25 to 40° F. per hour or higher.

The invention may be more readily understood by reference to the following examples given for the purpose of illustration and are not to be construed as limiting the invention in any manner whatsoever.

Example 1

A series of blends were made using a commercial separation aid and a separation aid of the present invention in an untreated Panhandle distillate having a viscosity of 62 seconds Saybolt at 210° F., which distillate represented about a 6% cut on the crude. Approximately 3 volumes of naphtha diluent were used per volume of Panhandle distillate and the respective blends were rapidly chilled to -44° F. The results of these tests after allowing the blends to settle for 16 hours were as follows:

Test	Settling aid	Percent settling aid based on waxy oil	Percent clear oil	Remarks
1.	None		0	Mixture almost solid.
2.	Commercial settling aid.	0.5	0	Mixture fairly viscous.
3.	do	1.0	Trace	Mixture fairly fluid.
4.	Wool fat	0.5	3.0	Do.
5.	do	1.0	14.0	Mixture quite fluid.

Example 2

Wool fats were secured from 9 different sources and were tested on an untreated Panhandle distillate having a viscosity of 67 seconds Saybolt at 210° F. In these tests approximately 3 volumes of naphtha were used per volume of distillate and the mixtures rapidly chilled to -36° F. The results of these tests were as follows:

Test	Percent inhibitor	Percent clear solution	Bath temp., ° F.
1.	None	Solid	-36
2.	1	48	-36
3.	1	65	-36
4.	1	49	-36
5.	1	55	-36
6.	1	60	-32
7.	1	60	-36
8.	1	52	-36
9.	1	45	-30
10.	1	72	-30

Example 3

78 parts by weight of wool fat were dissolved in about 740 parts by weight of fluxing naphtha and the mixture was rapidly chilled to -34° F. This mixture was then separated into 61% precipitate and 39% filtrate. These fractions were then tested as filtering aids in a Panhandle distillate having a viscosity of 50 seconds Saybolt at 210° F. Approximately 3 volumes of naphtha were used per volume of distillate and the respec-

tive mixtures were chilled rapidly to -36° F. The results of these tests were as follows:

5	Test	Kind of settling aid used	Percent of inhibitor	Percent clear solution	Remarks
1.		Original wool fat	0.5	0	
2.		do	1.0	35	Solid.
3.		Precipitate (61%)	0.5	55	
4.		do	1.0	60	
10	5.	Filtrate (39%)	0.5	0	Solid.
6.		do	1.0	0	Do.
7.		Blend of precipitate and filtrate.	0.5	0	Very viscous.
8.		do	1.0	40	

Example 4

15 Wool fat was distilled under vacuum conditions and 56% was taken overhead in five 10% cuts and one 6% cut, the final still temperature being 650° F. and a pressure of 0.1 inch mercury. 20 Cold settling tests were then run over a period of ten hours using a Panhandle distillate having a viscosity of 50 seconds Saybolt at 210° F. described in the preceding example using 3 volumes of naphtha per volume of oil with the following 25 results:

30	Test	Settling aid used	Percent settling aid based on waxy oil	Bath temp., °F.	Percent clear solution	Remarks
1.		None	None	-35	0	Solid.
2.		Original wool fat	0.5	-35	0	Very viscous.
3.		do	1.0	-35	35	
35	4.	do	2.0	-35	40	
5.		56% overhead	1.0	-35	0	Solid.
6.		50-56% overhead	1.0	-35	0	Do.
7.		44% bottoms	0.5	-35	55	
8.		do	1.0	-35	73	

Example 5

40 Wool fat was distilled in the manner described in Example 4 and the distillation was carried to 77% bottoms and a final still temperature of 590° F. at a pressure of 0.1 inch mercury. Settling aid tests were then run on these fractions in the manner described in Example 4 with the following results:

50	Test	Settling aid used	Percent settling aid based on waxy oil	Bath temp., °F.	Percent clear solution	Remarks
1.		77% bottoms	0.5	-35	15	
2.		do	1.0	-35	55	
55	3.	23% overhead	1.0	-35	0	Solid.
4.		Blend of 23% overhead and 77% bottoms	1.0	-35	46	

Example 6

60 A sample of a lube plant charge stock was blended with 1% of wool fat and fluxed with 3 volumes of naphtha per volume of said stock. This material was then chilled rapidly and the 65 material dewaxed by filtering. The dewaxed stock was then treated with 25 lbs. of 98% sul-

furic acid per barrel and contacted with 1 lb. per gallon of Gonzalas clay for two hours at 350° F. Inspections were then run on the filtered dewaxed oil and the results were as follows:

Gravity °A. P. I.	26.3	5
Flash, °F.	495	
Fire, °F.	575	
Viscosity Saybolt at 100° F.	736	
Viscosity Saybolt at 210° F.	72.4	10
Viscosity index	87	
Carbon, per cent	.44	
Robinson color, original	9 1/4	
16 hrs. at 250° F.	6 3/4	
16 hrs. at 250° F. of oil of average stability	5 1/4	15
Steam emulsion number	145	
Neutralization value	0.07	

From the above data it may be readily seen that the separation aid of the present invention 20 had no adverse effects on the quality of the dewaxed lubricating oil.

The above invention is not to be limited by any theory or mode of operation, but only by the following claims in which it is desired to 25 claim all novelty insofar as the prior art permits.

I claim:

1. A process for conditioning oils preparatory to the separation of wax therefrom which comprises mixing said wax and oil with a wax separation aid containing cholesterol.

2. A process for separating wax from wax-oil mixtures which comprises mixing the wax-oil mixture with a wax separation aid containing cholesterol, chilling the mixture to solidify the 35 wax content and separating the solidified wax from the oil.

3. A process for separating wax from wax-oil mixtures which comprises mixing the wax-oil mixture with a wax separation aid containing cholesterol and a diluent, chilling the mixture to solidify the wax content and separating the solidified wax from the oil.

4. A process as in claim 2 in which the wax separation aid comprises wool grease.

5. A process as in claim 2 in which the wax separation aid comprises lanolin.

6. A process as in claim 3 in which the wax separation aid comprises wool grease.

7. A process as in claim 3 in which the wax separation aid comprises lanolin.

8. A process for conditioning oils preparatory to the separation of wax therefrom which comprises mixing said wax and oil with a wax separation aid secured by dissolving wool fat in a fluxing medium, cooling the mixture rapidly, separating the precipitate and using the same as said wax separation aid.

9. A process for conditioning oils preparatory to the separation of wax therefrom which comprises mixing said wax and oil with a wax separation aid secured by distilling wool fat, segregating the bottoms and using the same as said wax separation aid.

WALTER W. MEYER. 65
